BLENDER JAR

Clarence Lee Folden, Downers Grove, Ill., assignor to Sears, Roebuck and Co., Chicago, Ill.

Filed June 12, 1970, Ser. No. 23,447

Term of patent 14 years

Int. Cl. D7—05

U.S. Cl. D89—1

Fig. 1

Fig. 2

Fig. 3

Fig. 4

Fig. 5

Fig. 6

Fig. 7

FIG. 1 is a side elevational view of a blender jar showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a cross-sectional view taken on line 6—6 of FIG. 1; and

FIG. 7 is a cross-sectional view taken on line 7—7 of FIG. 1.

I claim:

The ornamental design for blender jar, as shown.
